UNITED STATES PATENT OFFICE.

ADOLPH T. HEISER, OF WYOMING, PENNSYLVANIA.

MANUFACTURE OF SCOOPS.

SPECIFICATION forming part of Letters Patent No. 268,669, dated December 5, 1882.

Application filed August 14, 1882. (No model.)

To all whom it may concern:

Be it known that I, ADOLPH T. HEISER, of Wyoming, in the county of Luzerne and State of Pennsylvania, have invented certain new and useful Improvements in the Manufacture of Scoops; and I do hereby declare the following to be a full, clear, and exact description of the same, reference being had to the accompanying drawings, forming part of this specification, in which—

Figure 1 represents the flat blade blank; Fig. 2, the blade with the projection at the top drawn out; Fig. 3, the blade with the back strap welded onto the projection; Fig. 4, the blade with both front and back straps welded on, but before being pressed up into shape; Fig. 5, a view of a completed scoop.

Similar letters of reference in the several figures denote the same parts.

One method of manufacturing metal scoops heretofore practiced consists in striking up from a single piece of metal the blade and the back strap and then securing the front strap by means of rivets; but the forming of the back strap continuous with the blade is somewhat expensive and the attachment of the front strap to the blade by means of rivets is objectionable, because the rivets wear and become loose. In another method heretofore practiced a piece of flat metal with a V-shaped portion cut out at the top is heated and pressed up into the shape of a scoop-blade, and the front and back straps are also separately cut out and pressed to proper shape to fit the blade, and are then applied one at the front and the other at the rear of the blade, so as to cover the V-shaped space and leave room between them to receive the handle. This being done, the straps are fastened to the blade by means of rivets, the blade and straps are heated to welding heat, a mandrel is inserted between the two straps, and then by proper dies and pressure the straps are welded to the blade. This method requires a good many dies and a large amount of machinery, and the resulting article is a scoop having a large front strap as well as a large iron back strap, the latter being especially exposed to wear when using the scoop in coal, ore, &c. It has been my object to improve upon these prior methods and to produce at less trouble and expense

an article superior in finish and durability to any heretofore made.

In carrying out my invention I take a flat piece of sheet-steel, A, of proper size and shape to form the blade, and by a dead-stroke hammer or otherwise I draw out the steel, so as to form a small projection, a, of about one-fourth to one-half an inch in length at the top of the blade. To this projection I weld the narrow back strap, B, and to the front of the blade I weld the large front strap, C. The blade remains perfectly flat during the process of welding. I next heat the blade and insert a mandrel between the blade and the large front strap, C, in order to form a socket to receive the handle, and while the mandrel is still in position I place the heated blade between suitable dies, and by the application of power press the blade into shape; or I press the blade into shape first, and afterward introduce the mandrel to open up the socket.

It will be observed that by my mode of manufacture a scoop is produced having a solid steel back, and that the V-shaped piece usually cut out is utilized to form not only part of the solid steel back, but also a part of the socket which receives the handle, the front strap forming the other part of said socket.

The absence of shoulders and rivets in the implement obviates the liability of the straps becoming broken, loosened, or pulled off by the severest usage to which the implement may be subjected.

If it is desired to have the large strap C on the under or wearing side of the scoop and the solid steel surface on the inside of the scoop-bowl, it can be readily done by merely turning over the scoop-blade before pressing it into shape. It will be seen, therefore, that I can at will produce a scoop with the solid steel surface either on the inside or outside of the scoop-bowl.

Having thus described my invention, I claim as new—

1. The herein-described improvement in the art of manufacturing scoops, which consists in taking a blank of sheet metal of proper size and shape to form the blade and drawing from the metal of the blade a small projection at the top of the blade, welding a narrow strap to said projection, welding the broad strap to the

face of the blade, pressing by means of dies and pressure the heated blade into the ultimate scoop shape, and opening up a socket for the handle by inserting a mandrel between the 5 blade and the broad strap, either before or after pressing up the blade to its ultimate shape, substantially as described.

2. The herein-described scoop, consisting of the sheet-steel blade having the small projection

drawn out at the top, the narrow strap welded 10 to said projection, and the broad strap welded to the face of the blade and forming with the blade a socket for the handle, substantially as described.

ADOLPH T. HEISER.
